UNITED STATES PATENT OFFICE

EUGENE L. MESSLER, OF PITTSBURGH, PENNSYLVANIA

PRESS FOR PLASTIC MATERIALS

Application filed May 9, 1929. Serial No. 361,619.

This invention relates to a press for plastic materials, and more particularly to a die structure for use in seggar presses as employed in the manufacture of ingot mold 5 hot tops.

Ingot mold hot tops, according to their preferred form, require a seating shoulder, so that the hot top may rest on an ingot mold with a small portion thereof projecting into 10 the bore of the mold, and the major portion thereof projecting upwardly from the mold. This shoulder is formed by removing material from the outer and lower edge of the hot top, so that either a plurality of small ledges 15 are formed, or a continuous ledge is formed. The conformation of a short portion of the hot top to produce these ledges, presents the chief problem in the manufacture of hot tops in a seggar press. As the clay used contains 20 a great deal of moisture during the period of pressing, the use of a continuous ring of appreciable vertical extent results in pulling away the wall lying between such ring and the main body of the plunger, that is of the 25 male forming die, as such die is removed.

A structure obviating such difficulty is illustrated and described in patent to Austin L. Moore No. 1,698,603.

The object of the present invention is to 30 provide a simplified structure, which may be used in producing hot tops having seating ledges of suitable contour, and in forming the seating ledges of hot tops of certain contour and size.

In the accompanying drawings Figure I is 35 a vertical sectional view of the female forming die and an elevation of the male forming die, illustrating one modification in the structure of the male die; Figure II is a view partly in vertical section, and partly in elevation, showing the same die structure in seated or completed pressing position; Figure III is a view taken on the line III—III of Fig. I, showing the male die structure in 40 bottom plan; Figure IV is a view partly in elevation and partly in vertical section, showing the form of hot top pressed by the die structure of Figures I and II; Figure V is a view partly in vertical section and partly 45 in elevation, showing the die members in

pressing position, and illustrating the use of a continuous ring on the male die or plunger; Figure VI is a bottom plan view on a reduced scale showing a modified form of hot top made by a slightly modified die structure; 55 and Figure VII is an elevation of the hot top shown in Fig. VI.

With reference to Figs. I and II numeral 1 designates the female die of the press, which may be of any usual form, and reference numeral 2 the clay or other suitable plastic composition therein. Reference numeral 3 designates the plunger or male die proper, and reference numeral 4 the head carrying the same. 60

Carried by head 4 are ledge forming die blocks 5. These ledge forming dies, as shown particularly in Fig. III, are of a form to produce relatively short corner ledges of moderate depth, or vertical extent. As 70 shown, these die blocks 5 are spaced from the base portion of the male die, or plunger, a sufficient distance to leave a material space 6 between the die block and body of the plunger. The die thus cuts out the corners 75 6a in forming the hot top leaving a relatively thick wall of material in the space 6 adjacent such cut away portion.

By utilizing these dies to produce corner ledges 6b of small peripheral extent, the hot top when pressed is given sufficient seating surface, without experiencing the difficulties described above during the withdrawal of the plunger, or male die. The difficulty is avoided for the reason that the die arrangement is such as to leave a thick wall of material, and because the depth, or vertical extent, of the space 6 between the body of the plunger and each auxiliary die block is relatively short. 80

It has also been found that where the male die or plunger is given a relatively great degree of taper, a continuous ring may be utilized, provided that neither the vertical nor horizontal depth of the impression made by such die ring be relatively great with respect to the thickness of material lying between the die ring and the bottom of the plunger or male die. 85

It will be noted by reference to Fig. V 90

that the die ring 7 carried by head 4a is so positioned with respect to the base portion of the plunger, or male die, 3a that the impression made thereby is relatively short and narrow, leaving a relatively great body of material between the ring and plunger. It will be noted that while the die ring 7 is of considerable width in itself, the greater portion of such width seats in an annular recess 8 in the female die 1a. The effective width of the ring is thus the portion thereof which extends inwardly from the bore 1b of the female die. Because of the taper of the plunger, clearance is provided immediately upon the beginning of the withdrawing movement thereof.

For the above reason a hot top having an internally tapered bore, and a seating ledge which is relatively narrow and positioned relatively close to the lower edge of the hot top may be made by use of a male die structure with a continuous auxiliary ring. The draft, or angle of inclination of the male die, is varied in accordance with the consistency and inherent cohesion of the material used for the hot tops. With the mass commonly used, however, this angle should not be materially less than five degrees, and may be desirably increased in order to increase the factor of safety in preserving the wall portion, or flange 9, of the hot top extending below the seating ledges 14.

After removal of the pressed hot top from the seggar press, and before the same has hardened, a teeming orifice 10 is desirably cut in the upper horizontal wall 11 of the hot top.

To press the form of hot top shown in Figs. VI and VII of the drawings, it is not always necessary to employ a continuous ring 7, because additional auxiliary die blocks may be added to the head 4 between the corner die blocks 5. These blocks are similarly applied to the head 4 to leave a space corresponding to the wall portions 12 of the hot top between the inner face of the die block and the outer face of the adjacent portion of the plunger. It will be noted that these die blocks will obviously be so arranged as to leave a relatively great thickness of material to form the walls; and while they are of relatively great width it may be seen by the indentations 13 formed thereby that they are of relatively slight effective width with respect to the wall left by the interval between the die blocks and the surface of the male die proper.

While the angle of inclination of the male die proper 3, shown in Figures I, II, and III, is shown as equal to that of the male die proper 3a, shown in Figure V, such a degree of taper is not necessary. With that form of die structure, as with the structure to be used in forming the hot top of Figs VI and VII, the interruption between the die blocks,

obviously not present when a continuous ring is used, gives some relief and lessens the tendency for the lower wall portion, or flange, to pull away when the male die is withdrawn. This is particularly the case where mere corner indentations are to be made, as with the die structure shown in Figs. I to III inclusive. 70

What I claim is:

1. In a die structure for use in pressing plastic substances to form ingot mold hot tops the combination of a female die, a plunger head, a male die proper on said head arranged to form a centrally disposed indentation in plastic material lying in the female die, and auxiliary male die means rigidly mounted on said head and spaced from the male die proper; said auxiliary die means being arranged to cooperate with the female die to form an external shoulder in the material lying between the male die proper and the interior surface of the female die, and the auxiliary die means being so formed that the indentation produced thereby is of slight depth relatively to the depth of the indentation produced by the male die proper, there being an inclination in at least one of the opposed surfaces of the male die proper and the auxiliary male die means of no less than five degrees. 75

2. In a die structure for use in pressing plastic substances to form ingot mold hot tops the combination of a female die, a plunger head, a male die proper on said head arranged to form a centrally disposed indentation in plastic material lying in the female die, and auxiliary male die means rigidly mounted on said head and spaced from the male die proper; said auxiliary die means being arranged to cooperate with the female die to form an extended external shoulder in the material lying between the male die proper and the interior surface of the female die, and the auxiliary die means being so formed that the indentation produced thereby is of slight depth relatively to the depth of the indentation produced by the male die proper, there being an inclination in at least one of the opposed surfaces of the male die proper and the opposed auxiliary die means of no less than five degrees. 90

3. In a die structure for use in pressing plastic substances to form ingot mold hot tops the combination of a female die approximately rectangular in horizontal section, a plunger head, a male die proper on said head arranged to form a centrally disposed indentation in plastic material lying in the female die, and auxiliary male die means comprising corner blocks rigidly mounted on said head and spaced from the mold die proper to cooperate with the interior of the corners in the female die to form shoulders at such regions in the material between the male die 100

proper and the female die; said auxiliary corner blocks being so formed that the indentation produced thereby is of slight depth relatively to the depth of the indentation produced by the male die proper.

5 In testimony whereof I have hereunto set my hand.

EUGENE L. MESSLER.
